UNITED STATES PATENT OFFICE

FRANCIS M. VOLK, OF SAN FRANCISCO, CALIFORNIA, ASSIGNOR OF ONE-THIRD TO EVERETT P. PETERSON AND ONE-THIRD TO JAMES A. GREER, BOTH OF SAN FRANCISCO, CALIFORNIA

RAIL FROG

Application filed November 5, 1930. Serial No. 493,558.

This invention relates to rail frogs and especially to improvements on the structure shown in my former patent entitled "Railway frogs", issued February 28th, 1928, Patent No. 1,660,694.

The rail frog disclosed in the above entitled patent was particularly constructed to avoid or eliminate the use of guard rails in the construction of railway frogs and this was accomplished by the formation of an inward offset portion on the main and turn-out rails at a point contiguous to the frog point in a manner to guide the wheel flanges so that they would pass the frog point without danger of colliding therewith.

The object of the present invention is to generally improve and simplify the construction and operation of the type of railway frog disclosed in my former patent; to provide a railway frog in which offsetting of the main and turn-out rails at a point contiguous to the frog point may be entirely eliminated; and, further, to provide a railway frog in which collision between the wheel flanges and the point of the rail frog may be entirely avoided by offsetting the opposed converging faces of the frog point with relation to the main and turn-out rails adjoining the same.

The rail frog forming the subject matter of the present application is shown in the accompanying drawings, in which—

Fig. 1 is a plan view of the main and turn-out rails showing the frog structure connecting the same,

Fig. 2 is an enlarged plan view of the frog structure.

Referring to the drawings in detail and particularly Fig. 1, A indicates a road bed or ties on which are secured in the usual manner by spikes, or the like, a pair of main line rails B, and a pair of turn-out rails C. These rails intersect each other at D and the point of intersection forms the rail frog. The converging or opposed faces of the frog point indicated at 2 and 3 are usually parallel to and align with the inner faces 2a and 3a of the main and turn-out rails and it is due to this alignment that guard rails are

employed to prevent collision between the car wheel flanges and the frog point.

The frog structure shown in the present instance eliminates the necessity of employing guard rails, and it furthermore eliminates the necessity of offsetting the main and turn-out rails as shown in my former patent and it is accomplished by offsetting the opposed faces 2 and 3 of the frog point as shown in Fig. 2. The dotted lines indicated at 2b and 3b show the ordinary frog point employed, that is, a point having converging faces which align with the inner faces 2a and 3a of the main and converging rails. In the present instance it will be noted that the converging face 2 of the frog point is offset with relation to the dotted line 2b which represents a line aligning with the inner face of the main line rail 2a. It is here clearly shown that the face 2 of the frog point is offset in an outward direction, thus providing ample clearance for the flanges of the car wheels as they cross the intersection; the amount of clearance provided in actual practice being approximately a half inch.

Again, by referring to Fig. 2, it will be noted that the dotted line 3b represents a line which aligns with the inner face of the turn-out rail indicated at 3a. It will further be noted that the face 3 of the frog point is offset with relation to this line, hence providing ample clearance for the flanges of the car wheels, which are traveling on the turn-out rails. In other words, in place of offsetting the rails with relation to the frog point to provide clearance for the car wheel flanges a reverse construction has been resorted to inasmuch as the same result is accomplished by offsetting the opposed faces of the frog point; this can be accomplished by two different methods, first, by converging the opposed faces on a greater angle than has heretofore been resorted to, and secondly, by moving the frog point further away from the point of intersection. Ordinarily the opposed faces 2 and 3 of the frog point would be absolutely parallel to the inner faces of the main and turn-out rails, but as a greater angle of convergence is resorted to in the present instance a slight

angular relation is maintained between the opposed faces 2 and 3 and the inner faces of the main and turn-out rails. By offsetting the faces of the frog point the structure of the rail frog is simplified and a more rigid structure is obtained. Furthermore the cost of manufacture is considerably reduced as compared to the frog structure shown in my former patent where offsetting of the main and turn-out rails is an essential feature.

In actual practice, by referring to Fig. 1, it will be noted that a pair of wheels 6 are secured on a rigid axle 7 as indicated. The car supported by the wheels is proceeding in the direction of arrow *a* on the main line rails and as the flanges engage the inner faces 2a of the main line rails they will continue to travel in that direction, and as they cross the frog the flanges will travel along the dotted line indicated at 2b, see Fig. 2, thus passing the point of the frog with sufficient clearance to eliminate all danger of collision. The point of crossing is furthermore smooth and is accomplished without any jar, as offsetting of the rails has been eliminated and guard rails have also been eliminated both of which tend to impart a side motion to the wheel flanges during the crossing of a frog. Such side or lateral motion imparted by the guard rails or the offset portions in the rails throws a heavy strain not only on the rolling stock passing thereover but also on the rails and the fastening means employed and as such lateral motion or jar is entirely eliminated in the present instance, the life of the rails, the fastening means, and the rolling stock is materially increased.

While certain features of the present invention are more or less specifically described, I wish it understood that various changes may be resorted to within the scope of the appended claims. Similarly, that the materials and finishes of the several parts employed may be such as the manufacturer may decide, or varying conditions or uses may demand.

Having thus described my invention, what I claim and desire to secure by Letters Patent is—

1. In a structure of the character described, main and turn-out rails intersecting each other, and a frog point adjacent the point of intersection, said frog point converging on lines which are offset in an outward direction with relation to the planes of inner faces of the main and converging rails.

2. In a structure of the character described, main and turn-out rails intersecting each other, and a frog point adjacent the point of intersection, said frog point presenting opposed converging faces both of which are offset in an outward direction with relation to the planes of the inner faces of the main and turn-out rails.

3. In a structure of the character described, main and turn-out rails intersecting each

other, and a frog point adjacent the point of intersection, said frog point presenting opposed converging faces both of which are offset in an outward direction with relation to the planes of the inner sides of the main and turn-out rails, said converging faces disposed on an angle to the lines paralleling the inner faces of the main and converging rails.
